PORTABLE PARK BENCH

Henri Rush, St. Louis, Mo.

Application May 15, 1943, Serial No. 487,102

2 Claims. (Cl. 155—191)

My invention relates to a bench, such as those commonly used in public parks and other outdoor locations. Such benches have heretofore usually been provided with metal supports. Under present conditions the use of metal for such purposes must be avoided.

One of the objects of my invention is to provide a bench which may be made entirely from wood, with the exception of such nails or screws as may be found necessary or desirable to use in securing the parts of the structure together. And further, to keep the weight of the bench within such limits that it may be readily carried by two persons, thus retaining the portable feature of the benches heretofore in use.

Another object of my invention is to so construct the wooden supports for the bench that they may be made without the employment of wide boards.

Other objects of my invention relate to specific details of construction by means of which the necessary strength is secured with the use of a minimum amount of material.

In the accompanying drawing, which illustrates a bench made in accordance with my invention, Figure 1 is a front view; Figure 2 is an end elevation; Figure 3 is a section taken on the line 3—3 of Figure 1; Figure 4 is a section taken on the line 4—4 of Figure 2; and Figure 5 is a section taken on the line 5—5 of Figure 1 but showing a modification.

Each of the supports or end pieces is built up of two parts 6 and 7, thus avoiding the necessity of employing a wide board for this purpose. The part 6 projects above part 7 and serves to carry the back slats 8. The two parts of the support are secured together edge to edge along line 9. In addition to being united along line 9, parts 6 and 7 are connected by a shoe piece 10 secured to the lower edges of both parts. This shoe piece is made of hard wood, such as oak, which protects the supports against wear and against access of moisture from the ground upon which the shoes rest. While the other parts of the bench may be made of any kind of wood, I prefer to use clear kiln dried cypress free from defect.

The supports are spaced apart by a longitudinal brace 11 mortised into the longer parts 6, as shown at 12 (Figure 4). Secured on the upper edge of each of parts 7 is a cleat 13. These cleats have secured to them the seat slats 14 the position of which they determine. However, to give better form to the seat the rear slat 14' is preferably tilted by contact with the curved edge of part 6. The front slat 14 is given a similar tilt by beveling off the front ends of the cleats. The rear ends of the cleats extend beyond the junction of the two parts of the support and have slotted engagement with the upper edge of brace 11 as shown at 15. Located at the center of the bench is a vertical brace 16 L-shaped in form

and having one arm secured to the back slats 8, the other to seat slats 14. It also has slotted engagement with brace 11, as shown at 16', and is also attached to the latter brace.

The construction above described will be found to give ample rigidity in benches up to about ten feet in length. When longer benches are employed, I prefer to supplement the longitudinal brace 11 with another similar brace 11', as shown in Figure 5, this brace being placed adjacent to and parallel with brace 11. In such case it will be found advisable to employ more than one vertical brace 16.

In securing the various parts together, as above described, it is preferable to employ wood screws rather than nails. If, however, it is desired to eliminate all metal, non-metallic dowels may be substituted. In addition, the joints may be glued. This is particularly desirable in joint 9 between the two parts of the support. The entire bench should be smoothed and finished with enamel, both to improve its appearance and to protect it from weathering.

Having fully described my invention, what I claim as new and desire to secure by Letters Patent of the United States is:

1. In a device of the class described, a pair of supports each formed of long and short members joined together, the long members extending above the short members, the front edges of said long members being upwardly inclined at the points of junction with the short members, the two members of each support being connected by a transverse shoe piece attached to both members and contacting the ground, a horizontal brace extending between the supports, cleats secured to the short members of the supports and also engaging with the longitudinal brace, and seat slats secured to the cleats, the rear seat slat also engaging with the inclined edges of the long member of the support to tilt said slat relative to the other seat slats.

2. In a device of the class described, a pair of supports each formed of long and short members joined together, the long members extending above the short members, the two members of each support being connected by a transverse shoe piece attached to both members and contacting the ground, a horizontal brace extending between the supports and mortised into them, cleats secured to the short members of the supports and also engaging with the longitudinal brace, back slats secured to the long members of the supports, seat slats secured to the cleats, one of said seat slats also engaging with the long members of the supports to tilt said slat relative to the other seat slats, and a vertical brace positioned between the supports and secured to both the back slats and the seat slats, said vertical brace also engaging with the longitudinal brace.

HENRI RUSH.
